BLADE SHARPENER

Blackwell K. Murchison, Brooklyn, N. Y.

Application November 1, 1947, Serial No. 783,462

6 Claims. (Cl. 51—158)

1

This invention relates to new and useful improvements in blade sharpeners.

The new and improved blade sharpener makes use of a pair of face engaging adjacent abrasive plates constructed of plastic material having an abrasive substance embedded therein. It is proposed that these abrasive plates be provided with an opening between their faces which extends inwards from one of the ends of the plates. It is proposed to rotatively mount an eccentric on one of the plates within said opening. An important feature of this invention resides in the provision of a blade holder within said opening for holding a blade in sharpening position between the abrasive plates and mounted on said eccentric and provided with a handle extending out from said opening by which the holder may be moved in a rotary fashion.

Another object of this invention resides in providing the blade holder with elements for engaging and holding the blade. Several modified forms are shown which distinguish from each other in the construction of the holding elements on the blade holder.

The invention further contemplates constructing the blade holder of various designs and shapes for holding various types and kinds of blades. For example, the blade holder may hold a double edge razor blade, a single edge razor blade, and knives of various designs and constructions.

The invention contemplates manually moving the handle for operating the blade holder. However, a reciprocating motor may be used for this purpose.

Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a plan view of a blade sharpener constructed in accordance with this invention.

Fig. 2 is an elevational view of Fig. 1.

Fig. 3 is a transverse enlarged sectional view taken on the line 3—3 of Fig. 1.

Fig. 4 is a longitudinal enlarged fragmentary sectional view taken on the line 4—4 of Fig. 1.

Fig. 5 is a fragmentary enlarged vertical sectional view taken on the line 5—5 of Fig. 1.

2

Fig. 6 is a plan view of a blade sharpener constructed in accordance with a modified form of this invention.

Fig. 7 is a transverse enlarged sectional view taken on the line 7—7 of Fig. 6.

Fig. 8 is an elevational view of the blade holder used in Fig. 6, illustrated per se.

Fig. 9 is a fragmentary plan view of another blade sharpener constructed in accordance with another form of this invention.

Fig. 10 is an enlarged transverse sectional view taken on the line 10—10 of Fig. 9.

Fig. 11 is an elevational view of the blade holder used in Figs. 9 and 10.

Fig. 12 is a plan view of the blade sharpener illustrated in Figs. 6 to 8 to which a reciprocating motor has been applied for operating the handle.

The blade sharpener, in accordance with that form of the invention illustrated in Figs. 1 to 5 inclusive, includes a pair of face engaging adjacent abrasive plates 14 and 15 having an opening 16 between their faces and extending inwards from one of their ends. The plates 14 and 15 are hingedly connected at their other ends with a hinge construction 17. The plates 14 and 15 are of thermoplastic or thermo-setting material, preferably transparent, so that the sharpening operation may be viewed, as will be hereinafter more fully described.

It is proposed that abrasive material be embedded in the plates 14 and 15. This may be done by mixing an abrasive powder material with the powder plastic before it is molded, or the

abrasive powder material may be forced into the adjacent faces of the plates while temporarily softened. The opening 16 has inclined or sloping side portions 18 for engaging the edges of a blade 19 engaged between said plates for sharpening the edges of the blade when the blade is moved about. The blade 19, as illustrated, is a double edge razor blade.

An eccentric 20 is rotatively mounted on one of said plates, namely, the plate 15. This eccentric 20 is disposed within the opening 16. The eccentric 20 comprises a disc 21 rotative in a circular recess 22 formed inwards from the inner face of the plate 15. A stud 23 at the bottom of the disc 21 rotatively engages through the plate 15 by which the disc is rotatively mounted. The disc 21 is provided with a projecting pin 24 located at an eccentric position.

A blade holder 25 is disposed within the opening 16 for holding said blade 19 in sharpening positions between said abrasive plates 14 and 15.

Said blade holder 25 is mounted on the eccentric 20 which guides it in a circular path. The blade holder 25 is also provided with a handle 26 by which it may be conveniently moved. This handle 26 extends out from the opening 16.

The blade holder 25 is in the nature of a flat strip of material which is provided with a pair of holding elements 27 such as projecting lugs 27. These elements 27 are adapted to engage openings 28 formed in the blade 19. The blade holder 25 is also provided with a small arcuate opening 29, to provide a little tolerance, into which the pin 24 projects. The plates 14 and 15 are releasably held together with clasps 30. Each clasp 30 comprises a hook-like projection 31 from the plate 15 engaging a complementary cutout 32 formed in the plate 14.

The operation and use of the blade sharpener may be understood from the following:

The handle 26 may be manually reciprocated so as to cause the eccentric 20 to rotate so as to guide the blade holder 25 in a circular fashion. Since the blade 19 is mounted upon the blade holder 25 it will move correspondingly and the edges of the blade will be sharpened by engaging the sloping side portions 18 of the opening 16. After the blade 19 is sharpened the plates 14, 15 may be manually opened by forcing them apart so that the latches 30 open. Then the plate 14 may be swung about the hinge 17 so as to completely expose the blade 19 which may then be removed. The blade holder 25 may also be removed, if desired, merely by lifting it upwards to disengage the arcuate opening 29 from the pin 24.

In Figs. 6 to 8 inclusive a modified form of the invention has been disclosed which distinguishes from the prior form in the construction of the blade holder 35. This blade holder is provided with holding elements for engaging a blade, in the nature of a thickened inner portion 36 formed with a slot 37 through which the blade may be engaged. A blade 38 is illustrated engaged in the blade holder 35 by engaging through the slot 37. The blade holder 35 has a handle 39 by which it may be operated. The blade 38, as illustrated, is a single edge razor blade.

In other respects this form of the invention is identical to the prior form and identical parts may be recognized by the same reference numerals. However, the adjacent abrasive plates 14' and 15' are formed with an opening 16' between their adjacent faces which extends inwards from one of the ends of the plates. This opening 16' has sloping side portions 18, and an enlargement 40 for receiving the thickened or back side of the one edge razor blade 38.

In Figs. 9 to 11 inclusive, another form of the invention has been disclosed. In this form the blade sharpener includes a pair of face engaging adjacent abrasive plates 42 and 43 which are hingedly connected at one of their ends by a hinge construction 44. The plates 42 and 43 are long enough to accommodate a knife 45, to sharpen said knife. An opening 46 is formed between the adjacent faces of the plates 42 and 43 and extends inwards from one of the ends of said plates. This opening 46 has sloping side portions 47 for engaging the cutting edge of the knife 45 for sharpening it. An eccentric 48 is rotatively mounted on one of the plates, namely, the plate 43. This eccentric 48 comprises a disc 49 rotatively supported by a stud 50. This disc 49 is provided with a pin 51 eccentrically positioned.

A blade holder 52 is disposed within the opening 46 and is for the purpose of holding the knife 75 connected with said holder and extending out

45 in sharpening position between the abrasive plates 42 and 43. Said blade holder 52 is formed with a slot 54 into which the knife 45 may be engaged. The blade holder 52 is provided with a handle 55 projecting from the opening 46 by which the blade holder may be moved. The blade holder 52 is also provided with an opening 56 for engaging upon the eccentric pin 51. The plates 42 and 43 are releasably held together with a catch 57.

The operation and use of this blade sharpener may be understood from the following:

A knife 45 is placed within the blade holder 52 so that the handle of the knife rests on the handle 55 of the blade holder, and the blade of the knife extends into the slot 54. The handle 55 and the knife 45 may be manually held together and these parts may be reciprocated so as to cause the eccentric 48 to move the blade holder 52 in a circular path for sharpening the edge of the knife 45 between the sharpening side portions 47. The abrasive plates 42 and 43 may be opened by causing the catch 57 to open. Now the knife 45 may be removed from the blade holder 52.

In Fig. 12 another embodiment of the invention has been disclosed in which the blade sharpener, which is illustrated in Figs. 6 to 8, is shown connected with an electric reciprocating motor 58. This motor connects with the handle 39. When the motor 58 operates the handle 39 will be reciprocated and the eccentric will move the blade in a circular path.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said eccentric, and a handle for moving said holder connected with said holder and extending out from said opening.

2. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said eccentric, and a handle for moving said holder connected with said holder and extending out from said opening, said blade holder having elements for engaging and holding said blade.

3. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said eccentric, and a handle for moving said holder connected with said holder and extending out

70 from said opening, said blade holder having elements for engaging and holding said blade.

from said opening, said blade holder having projecting pegs for engaging into openings in said blade.

4. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said eccentric, and a handle for moving said holder connected with said holder and extending out from said opening, said blade holder having a slot through which said blade may be engaged and by which the blade is held in position.

5. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said

eccentric, and a handle for moving said holder connected with said holder and extending out from said opening, said blade holder having a slot through which said blade may be engaged and by which the blade is held in position, said slot being open at one end whereby a knife blade may be engaged in said holder and the handle of the knife may rest upon said handle.

5. A blade sharpener, comprising a pair of face engaging adjacent abrasive plates having an opening between their faces extending inwards from one of the ends of said plates, an eccentric rotatively mounted on one of said plates within said opening, a blade holder within said opening for holding a blade in sharpening position between said abrasive plates and mounted on said eccentric, and a handle for moving said holder connected with said holder and extending out from said opening, said abrasive plates being of thermo-plastic material with abrasive material embedded therein.
